MULTICOLOR STENCILING APPARATUS

Henry W. Schneider and Edward R. Lowndes,
Toledo, Ohio, assignors to Libbey Glass Com-
pany, a corporation of Ohio

Application July 2, 1937, Serial No. 151,674

9 Claims. (Cl. 101—115)

The present invention relates to stenciling apparatus designed for use in applying vitreous enamel compositions or paints to articles of glassware such as tumblers, jars, bottles and the like, 5 and to other articles of a vitreous or ceramic nature in the multi-color decoration thereof by a stenciling process.

More specifically, the invention relates to a 10 reciprocable stencil screen capable of movement relative to the article undergoing decoration and having permeable portions through which the decorating material is transferred to the article by the spreading action of a squeegee which is 15 maintained in contact with the screen along the line of contact between the screen and surface of the article undergoing decoration.

The principal object of the invention is to provide an apparatus of the above mentioned type 20 which is adapted for multi-color application and which is capable of applying two or more differently colored designs, or the component colors of a single design, to opposite, adjacent, or spaced regions on the surface of an article. Toward 25 this end, the invention contemplates the provision of an apparatus having a reciprocable stencil screen which is divided into a plurality of color applying regions through which differently colored decorating materials are respectively and 30 simultaneously forced onto the surfaces of respective articles by the spreading action of a like number of squeegees, all of which squeegees are maintained in stationary contact with their respective color applying regions during reciprocation 35 of the stencil screen. The articles are progressively operated upon in the apparatus in the different color applying regions of the screen and, after the last color application has been made thereon, they are removed from the apparatus.

It is another object of the invention to provide a stenciling apparatus having a reciprocable stencil screen and a squeegee therefor in which there is incorporated an improved form of automatic means for elevating the squeegee from the 45 stencil screen upon completion of each application of decorating material to the article.

Other objects of the invention will become apparent hereinafter.

50 In the accompanying drawings:

Fig. 1 is a top plan view of a stenciling apparatus manufactured in accordance with the principles of the present invention;

Fig. 2 is a front elevational view of the apparatus shown in Fig. 1;

Fig. 3 is a sectional view taken substantially along the line 3—3 of Fig. 1;

Fig. 4 is a sectional view taken substantially along the line 4—4 of Fig. 3; and

Fig. 5 is a fragmentary view, diagrammatic in its representation, of a pair of squeegee elevating devices employed in connection with the present invention.

The apparatus involves in its general organization a table or base 10 in the form of an elongated, substantially rectangular, casting. A bifurcated bracket 11 (Fig. 3) is bolted to the base 10 in the medial regions thereof and serves to support a horizontally disposed rock-shaft 12 between the furcations thereof. A supporting arm 13 has one end pivoted to the rock-shaft 12 and the other end thereof is pivotally connected to a link 30 by means of which it is suspended from and supported by a plunger latch mechanism 14 which will subsequently be described. A plate 15 is secured to the arm 13 in the medial regions thereof and a pair of article supporting units 16 are adjustably mounted on the plate 15 in spaced relationship. Opposed pairs of rollers 17 and 18 serve to support therebetween the articles T to be decorated.

The entire article supporting assembly just described is adapted to be lowered by pivotal movement of the same about the axis of the rock-shaft 12 and in order to facilitate lowering thereof, the arm 13 is connected by means of a link 19 to a treadle mechanism (not shown) disposed beneath the base 10.

A pair of open, rectangular, frame-like supporting members 20 (Figs. 1 and 3), each having laterally extending arms 21, are bolted or otherwise secured to the table 10 adjacent the opposite ends thereof. The arms 21 serve to support therebetween a pair of front and rear transversely extending horizontal tracks 22 and 23 respectively which are substantially coextensive with the table 10 which they overlie.

Supported tractionsally upon the tracks 22 and 23, and movable therealong in either direction transversely of the apparatus, is a stencil screen carriage 24 having associated therewith a stencil screen S adapted to occupy a position in the apparatus in tangential rolling line contact with the articles T rotatably supported on the units 16 therebeneath. The carriage 24 includes supporting wheels 25 which ride upon the tracks 22 and 23 and which are mounted on a pair of opposed side bars 26 of the carriage. The stencil screen S is carried by an open rectangular frame 27 (Fig. 1) which is divided into two color applying

regions R^1 and R^2 by means of a bar 28 which extends across the frame 27. Each color applying region is adapted to have placed thereon a quantity of a vitreous enamel decorating material. The material applied to the region R^1 is of a different color from the material applied to the region R^2 in order that the design which is applied to the article T may be of a multi-color nature. The frame 27 is supported by means of a plurality of suspension brackets 29 from the opposite pairs of parallel side bars 26 and 31 of the carriage 24.

An integral extension 35 (Fig. 1) formed on the table 10 serves to support thereon a pair of spaced uprights 36, the upper ends of which are bifurcated and overlie the rear track 23. Each upright 36 serves to support a rock-shaft 37 between the furcations thereof. A pair of squeegee arms 38 and 39 respectively are rockably mounted on the rock-shafts 37 by means of integral sleeves 40 formed on the rear ends thereof and through which sleeves the respective rock-shafts 37 extend. A pair of squeegees S^1 and S^2 are carried by the squeegee arms 38 and 39 respectively and overlie the respective color applying regions R^1 and R^2 of the stencil screen S in operative decorative relation thereto.

The squeegees S^1 and S^2 , which operate successively to force coloring material through the pervious portions of the screen and onto the surface of the respective articles T, in their respective color applying regions R^1 and R^2 of color application, are adapted to simultaneously traverse these regions upon reciprocation of the screen S in either direction. After the squeegees have completed their color applying operation it is necessary that the same be elevated from the coloring material on the screen prior to movement of the latter to either of its extreme positions so that upon return movement of the screen and operative engagement thereof by the squeegees, the coloring material on the screen in the regions R^1 and R^2 will occupy positions in advance of the respective squeegees S^1 and S^2 .

This clearing operation just referred to, and the maintenance of the squeegees out of contact with the screen when the latter is in either of its extreme positions is accomplished by the provision of a plurality of squeegee elevating and supporting members 41 (Fig. 5) which are arranged in pairs, one pair for each squeegee arm. The members 41 are secured to the forward side bar 31 of the carriage assembly 24 adjacent those regions of the screen S which are to be cleared by the squeegees S^1 and S^2 . Each member 41 (Figs. 1 and 5) comprises a face plate 42 having pivoted thereto a lifting cam piece 43 which normally occupies an inclined position and which loosely rests upon a pin 44 secured on the plate 42. Each squeegee arm 38 and 39 is provided with a forwardly projecting pin 45 which is adapted to be engaged by one or another of the cam pieces 43 upon movement of the carriage 24 in one direction or the other in such a manner that the pin 45 rides upwardly over the cam piece 43 and falls by gravity onto a rest 46 formed on the plate 42. Upon movement of the screen in the other direction, the pin 45 moves off of the rest 46 and the squeegee rides downwardly on an incline 47 formed on the plate 42 and comes into contact with the screen S in its respective region of color application. As the pin 45 passes the cam piece 43, the latter trips lightly over the same with no effect whatsoever thereon, and thus the squeegee is not disturbed or elevated from the

screen once it has made contact therewith preparatory to traversing its respective color applying region.

Referring now to Fig 1, it will be seen that with the carriage 24 in the extreme right hand position indicated, the squeegee arms 38 and 49 overlie the respective tumblers T supported in the units 16 beneath the screen S in their respective color applying regions R^1 and R^2 . The screen S is slightly spaced from the surfaces of the tumblers 10 T and means is provided for elevating the entire article supporting assembly a slight distance in order to close the gap existing between the screen S and the tumblers T. This elevation of the article supporting assembly, together with the pressure exerted by the squeegee upon the screen when the same are lowered into operative decorative engagement therewith, and which causes the screen to become fixed, permits the surfaces of the tumblers T to make tangential rolling line 20 contact with the screen when the same is moved in either direction.

Additionally, in order that the commencement and termination of each application of color to the opposite sides of the tumbler T shall not be 25 left to the discretion of the operator of the apparatus, means is provided for arresting movement of the carriage after the color applying regions R^1 and R^2 have been traversed by their respective squeegees S^1 and S^2 .

The means for elevating the article supporting assembly and for arresting movement of the carriage 24, just referred to, comprises the plunger latch mechanism 44, previously mentioned, together with a latch bar 50 (Fig. 2) which cooperates therewith. The latch bar 50 is suspended from the front side bar 26 of the carriage 24 and is movable therewith. An elongated slot 51 is formed in the latch bar 50 and the length thereof depends upon the extent or amplitude 49 of movement of the screen carriage.

The plunger latch mechanism 44 is supported at the upper end of a bracket 52 (Fig. 3) which is bolted or otherwise secured to the forward edge of the table 10. The latch mechanism consists of a cylinder 53 (Fig. 4) in which there is disposed a lower plunger 54 to which the link 31 that supports the forward end of the article supporting arm 13 is attached. The plunger 54 is normally maintained in an elevated position 50 by means of a coil spring 55 and is adapted to be lowered upon lowering of the article supporting arm 13 when the treadle mechanism (previously mentioned) is actuated. An upper plunger 56 is connected to the lower plunger 54 by 55 means of a pin and slot connection 57 and is normally maintained spaced from the lower plunger and extended from the cylinder 53 by means of a coil spring 58 of less capacity than the coil spring 55. The plunger 56 bears against 60 the underneath side of the latch bar 50 and slides therealong as the carriage 24 is reciprocated. The pressure of the coil spring 58, acting upon the coil spring 55, serves to limit the extent of upward movement of the plunger 54 and consequently the upper surfaces of the tumblers T are maintained close to the lower surface of the screen but out of contact therewith. Shortly after the carriage 24 has commenced its stroke in either direction and the squeegees have come 70 into contact with their respective color applying regions R^1 and R^2 , the upper plunger 56 encounters the slot 51 and is projected upwardly therethrough, thus releasing the pressure of the spring 58 on the spring 55 and permitting the 75

latter to expand and raise the plunger 54 to close the gap existing between the tumblers T and the screen S. The upper plunger 56 remains in the slot until both color applications of the design 5 or designs have been made on the respective tumblers T.

As the extreme end of the slot 51 engages the upper plunger 56, the carriage 24 is abruptly halted and the operator must actuate the treadle 10 mechanism to lower the tumbler supporting assembly and thus remove both tumblers T from engagement with their respective color applying regions R¹ and R² of the screen S. At the same time, the upper plunger 56 is withdrawn from 15 the slot 51 by virtue of the pin and slot connection 57 to enable the carriage 24 to be moved to its extreme position on the tracks 22 and 23.

As has been previously stated, the differently colored designs or the component colors of the 20 single design which are to be applied to each article T are stenciled upon the articles progressively by the expedient of transferring the articles from one supporting unit 16 to the other. In order that the second design or color application 25 shall be properly positioned upon the articles, a locating pin 60 or pointer is adjustably clamped by means of a set screw 61 to the unit 16 of the color applying region R².

A pair of handles 62 are mounted on the forward ends of the carriage side bars 26 to facilitate manual reciprocation of the carriage 24. Limit stops 63 are adjustably mounted on the forward track 22 by means of set screws 64 to 35 vary the amplitude of reciprocation of the carriage 24. These limit stops are adapted to be engaged by the front wheels 25 of the carriage to determine the extreme positions thereof.

In the operation of the apparatus, a tumbler T to be decorated is placed upon the article supporting unit 16 beneath the color applying region R¹, a partially decorated tumbler T being supported on the article supporting unit 16 beneath the color applying region R². Upon release of the foot treadle mechanism, the plate 15 (Fig. 2) 40 assumes a substantially horizontal position and the articles remain supported on their respective units 16 with their surfaces slightly spaced from the underneath side of the screen S in the respective color applying regions R¹ and R² thereof. With the carriage 24 in the position indicated in 45 Fig. 1, the upper plunger 56 (Figs. 2 and 4) bears against the underneath side of the latch bar 50 adjacent one end thereof. In this position of the carriage, the pins 45 of the squeegee arms 38 and 39 (Fig. 1) are supported directly upon the rests 46 of the squeegee elevating members 41 and thus both squeegees S¹ and S² are held 50 out of contact with the screen.

In order to commence the decorating operation 60 and apply the differently colored designs or the component colors of a single design to the respective tumblers T supported in the units 16, the operator engages one of the handles 62 and moves the carriage 24 toward the left on the tracks 22 and 23. The pins 45 of the squeegee arms 38 and 39 simultaneously move from the 65 rests 46, travel downwardly on the inclines 47, and come into contact with the upper surface of the stencil screen in their respective color applying regions R¹ and R².

Shortly after movement of the carriage 24 has commenced, the upper plunger 56 is released into the slot 51 and the release of downward pressure on the lower plunger 54 formerly exerted by the 70 75 coil spring 58 permits the coil spring 55 to expand

and raise the entire article supporting assembly until the tumblers T engage the underneath side of the screen S in the respective color applying regions R¹ and R².

Movement of the carriage 24 along the tracks 5 22 and 23 forces the coloring material placed upon the screen in the regions R¹ and R² through the screen and onto the respective surfaces of the tumblers T by the spreading action of the two squeegees S¹ and S².

After the respective designs or the component colors of the single design have been applied to the tumblers T, the upper plunger 56 engages the end of the slot 51 and motion of the carriage 24 is abruptly terminated. The operator must then 10 depress the treadle mechanism before the carriage can be moved to its extreme position. This being done, the pins 45 mounted on the ends of the squeegee arms 38 and 39 ride upwardly on the cam pieces 43 of the members 41, pass completely 15 thereover, and fall by gravity onto the rests 46 as the carriage reaches its limiting position. Thus the squeegees S¹ and S² are caused to clear the enamel composition on the screen in their respective color applying regions R¹ and R².

At this stage in the decoration of the tumblers, the completely decorated tumbler T is removed from the supporting unit 16 and the partially decorated tumbler is transferred to the unit which is vacated by the removal. An undecorated tumbler is substituted for the partially decorated tumbler. The foot treadle is again actuated and the entire operation just described is repeated but with the stencil screen carriage 24 moving in the opposite direction.

Modifications may be resorted to within the spirit and scope of the appended claims. For example, while the improved multi-color decorating apparatus has been shown and described in connection with an apparatus of the type employing a reciprocable stencil screen which moves horizontally in a straight line, the invention, by slight modification thereof, may be adapted for use in an apparatus of the type employing an oscillating 40 stencil screen which oscillates about a fixed 45 center.

We claim:

1. In a multi-color stenciling apparatus, a stencil screen movable in its own plane and provided with spaced pervious portions, means for supporting a plurality of articles having curved surfaces in tangential rolling line contact with said screen, and a squeegee for each pervious portion of the screen.

2. In a multi-color stenciling apparatus, a stencil screen movable in its own plane and provided with spaced pervious portions, means for supporting a plurality of articles having curved surfaces in tangential rolling line contact with said screen, and a relatively stationary squeegee for each pervious portion in contact with said screen, said squeegees being adapted to traverse their respective pervious portions of the screen upon movement of the latter.

3. In a multi-color stenciling apparatus, a stencil screen movable in its own plane and provided with spaced pervious portions, means for supporting a plurality of articles having curved surfaces in tangential rolling line contact with said screen, and a plurality of relatively stationary squeegees in contact with said screen, said squeegees being spaced apart a distance equal to the distance between corresponding points on said pervious portions of the screen.

4. In a stenciling apparatus, a reciprocable stencil screen movable in its own plane from one extreme position to another, said screen being divided transversely to its direction of movement into adjacent color applying regions, a squeegee for each color applying region, means for supporting a plurality of articles having curved surfaces in tangential rolling line contact with said screen, and means operable upon movement of said screen in one direction for causing said squeegees to simultaneously traverse their respective color applying regions in operative decorating contact with said screen.

5. In a stenciling apparatus, a reciprocable stencil screen movable in its own plane from one extreme position to another, said screen being divided transversely to its direction of movement into adjacent color applying regions, a squeegee for each color applying region, and means operable upon movement of said screen in either direction for causing said squeegees to simultaneously traverse their respective color applying regions in operative decorating contact with said screen.

6. In a multi-color stenciling apparatus, a stencil screen movable in its own plane, said screen being divided into a plurality of color applying regions through which differently colored decorating materials are adapted to be respectively forced, a relatively stationary article support positioned beneath said stencil screen, means on said support for supporting a plurality of articles having curved surfaces in tangential rolling line contact with said screen in the respective regions of color application, and a plurality of relatively stationary squeegees in contact with said screen in the respective regions of color application.

7. In a multi-color stenciling apparatus, a stencil screen movable in its own plane and provided with spaced pervious portions through which differently colored decorating materials are adapted to be forced, an article supporting carriage, means on said carriage for supporting a plurality of articles having curved surfaces in tangential rolling line contact with the screen, a squeegee for each pervious portion of the screen, and means for moving said carriage away from said screen to remove the articles supported

thereby from contact with said screen simultaneously.

8. In a stenciling apparatus, a reciprocable stencil screen carriage including a stencil screen movable with the carriage in its own plane in opposite directions from one extreme position to another, means for supporting an article having a curved surface in tangential rolling line contact with said stencil screen, a relatively stationary squeegee in contact with said screen for forcing coloring material placed on said screen through the latter and onto the article, said squeegee being movable to a position out of contact with said screen to clear the coloring material thereon, a cam member pivoted to said carriage, means for supporting said cam member so that one surface thereof is inclined upwardly, and a finger on said squeegee positioned in the path of movement of said inclined surface, said finger being adapted to be engaged by said surface as said carriage moves in one direction, a rest on said carriage in the vicinity of said cam member onto which said finger falls prior to a change in direction of movement of the carriage, said cam member being adapted to trip over said finger as said carriage moves in the opposite direction.

9. In a stenciling apparatus, a reciprocable stencil screen carriage including a stencil screen movable with the carriage in its own plane in opposite directions from one extreme position to another, means for supporting an article having a curved surface in tangential rolling line contact with said stencil screen, a relatively stationary squeegee in contact with said screen for forcing coloring material placed on said screen through the latter and onto the article, said squeegee being movable to a position out of contact with said screen to clear the coloring material thereon, a cam member pivoted to said carriage, means for supporting said cam member so that one surface thereof is inclined upwardly, and a finger on said squeegee positioned in the path of movement of said inclined surface, said finger being adapted to be engaged by said surface as said carriage moves in one direction, said cam member being adapted to trip over said finger as said carriage moves in the opposite direction.
